UNITED STATES PATENT OFFICE.

GEORGE B. BURCH, OF NEW YORK, N. Y., ASSIGNOR TO LESLIE STEVENS, OF GLEN RIDGE, NEW JERSEY.

PHONOGRAPH.

Application filed March 8, 1918. Serial No. 221,285.

To all whom it may concern:

Be it known that I, GEORGE B. BURCH, a citizen of the United States, and a resident of the city of New York, county of Kings, 5 and State of New York, have invented a new and useful Improvement in Phonographs, of which the following is a specification.

The object of my invention is to provide a 10 simple device of this class which will be simple in construction and accurate and reliable in operation. This object is accomplished by my invention, one embodiment of which is hereinafter more particularly set 15 forth.

For a more particular description of my invention, reference is to be had to the accompanying drawings, forming a part hereof, in which,

20 Figure 1 is a sectional view of a structure embodying my invention,

Figure 2 is a sectional view of a diaphragm,

25 Figure 3 is a view, partially in section, showing the needle and some attached and connected parts.

Throughout the various views of the drawings, similar reference characters designate similar parts.

30 My improved phonograph 1 is provided with a casing 2, a suitable motor 3, from which extends upwardly a spindle 4 on which is mounted a table 5 of the conventional kind, which carries a record 6 in the 35 usual manner.

At one side of the table 5 is placed a bracket 7 which has a hinge 8 pivoted therein and a pair of rings 9 affixed to the hinge 8 and these have the free edge of a diaphragm 10 sandwiched in between them. 40 The diaphragm is a large, direct-acting, diaphragm requiring no amplifying device, that is, it is of a size to produce sounds of the desired volume by setting up sound waves directly in the surrounding atmosphere. A size of from nine inches to a foot in diameter has been found most desirable for phonograph reproducers. The diaphragm is of conoidal form, its outer surface, that is, the 45 surface on the bulging, or convex, side of the diaphragm, being concavely curved from the apex of the diaphragm outward in all

radial directions. The central portion of the diaphragm is thicker than the portions nearer its periphery.

55

Near the rings 9, it is provided with a gutter 11 which is thin compared with the center so as to permit the diaphragm to respond accurately to vibrations which may be imparted to it by a needle bar 12 which is fixed to the diaphragm 10 by a proper means.

The needle bar 12 is mounted in a tube 13 by means of the perforated washers 14 and 15 which are secured at the lower end of said tube 13, and provided with a spherical seat 65 between them which contains a ball 16 which is fixed to the needle bar 12 in any proper manner.

The lower end of the needle bar 12 is provided with a suitable needle holder 17 which holds a needle 18 that is adapted to 70 engage a record 6. This needle holder 17 is provided with a suitable needle holding clamp 19 which may be of the form shown or any other suitable form. This holder is also provided with a laterally extending collar 20 which is engaged by a coil spring 21 which presses against this shoulder and also against the washer 15, as indicated. This spring 21 is a compression spring which performs the function of holding the needle 75 holder 17 at all times true upon the needle bar 12.

The tube 13 is supported from the rings 9 by means of a spider 22 having laterally extending arms 23 that are secured to the 80 rings 9 by screws 24 and washers 25.

In view of the foregoing, the operation of my improved phonograph will be readily understood. Assuming the parts to be as shown in Figure 1, and the table 5 turning in the 90 conventional manner, sound vibrations are transmitted along the needle bar 12 to the diaphragm 10 at the center, the diaphragm being thereby caused to vibrate and to set up the desired sound waves in the surrounding or adjacent atmosphere.

95 While I have shown and described one embodiment of my invention, it is obvious that it is not restricted thereto, but is broad enough to cover all structures that come within the scope of the annexed claims.

100 What I claim is:

1. An acoustic device, comprising a large, direct-acting vibratory diaphragm of conoidal form, its outer surface being concavely curved from the apex of the diaphragm outward in all

oidal form the outer surface of which is concavely curved from its apex outward in all radial directions.

2. An acoustic device, comprising a large, direct-acting vibratory diaphragm of conoidal form the outer surface of which is concavely curved from its apex outward in all radial directions, the central portion of the

diaphragm being thicker than the portions nearer its periphery. 10

3. A sound reproducer, comprising a large, direct-acting vibratory diaphragm of conoidal form the outer surface of which is concavely curved from its apex outward in all radial directions.

GEORGE B. BURCH.
